UNITED STATES PATENT OFFICE.

JOSEPH V. ROBINSON, OF NEW YORK, N. Y.

AUTOMATIC TRAIN-PIPE CONNECTER.

Application filed March 10, 1920, Serial No. 364,843. Renewed August 18, 1925.

To all whom it may concern:

Be it known that I, JOSEPH V. ROBINSON, a citizen of the United States, and a resident of the city of New York, State of New York, have invented certain new and useful Improvements in Automatic Train-Pipe Connecters, of which the following is a specification.

My invention relates to automatic train pipe connectors, for automatically coupling the air and steam pipes between railway cars, though it may be used for effecting such coupling between electrically hauled cars. An object of my invention is to improve the coupling head of such connectors, and more especially to simplify the construction of such heads whereby the cost of manufacture may be materially reduced, and uniformity of construction in large quantities readily attained. In an equipment of this character efficient interchange between mating heads, made at sundry and various times, must be certain and dependable. For that reason it is essential that the design of the head be such as to readily assure uniform construction. To attain this object is the purpose of my invention, and to that end I provide what is known as a butt face coupling head having separately constructed guiding prongs. Heretofore, such prongs have been constructed integrally with the base of the coupling head. Such design produces a construction difficult to successfully cast, and requiring a large amount of expensive machine work to attain uniformity of construction and interchangeability. To remove these obstacles, I construct my improved coupling head of three pieces, consisting of a pair of independent wings and a base. This construction greatly facilitates the economic and uniform manufacture of the coupling head and produces a rugged and durable construction offering the maximum service efficiency and dependable interchangeability.

My improvement consists of the arrangements, combinations, and constructions hereinafter described, pointed out in the appended claims, and illustrated in the accompanying drawings in which,—

Figure 1 is a side elevation of my improved coupling head showing some of the parts in section.

Figure 2 is a front face view of the construction shown in Figure 1. In this view the upper wing of my improved coupling

head is shown in section taken on the line 2—2 of Figure 1 while sections of the lower wing are shown as taken on the lines a—a, b—b, and c—c of Figures 2 and 3.

Figure 3 is a plan view of the construction shown in Figure 1.

Figure 4 is a rear view of the construction shown in Figure 1 with the wings or prongs partly broken away, and

Figure 5 is a vertical section through the structure shown in Figure 4 and taken on the line 5—5 of Figure 4.

Referring now to the drawings:

Any suitable form of flexible support A may be used to yieldingly support my improved coupling head. I preferably employ a support such as shown in my co-pending application, Serial 342,806, filed Dec. 5, 1919, comprising a laterally diverging hollow conduit 6, threadingly connected to my improved coupling head, as illustrated particularly in Figures 1, 3 and 5.

My improved coupling head comprises a base B having three vertically aligned ports or orifices 7, 8, 9 provided at their forward face with a suitable gasket 10, which projects slightly in advance of the coupling face 11 of the base B. Concentric with the ports 7, 8 and 9 I provide on the rear side of the base B nipples 12, 13 and 14, each extending rearwardly from the base on the longitudinal axis of each of the said ports as illustrated especially in Figures 1, 3, 4 and 5. Each of these ports is threaded to receive a suitable fitting with which to connect the ordinary train pipe of the car to my improved coupling head, the central port 8 being threaded to receive the curved conduit 6 of the support A. Diagonally spaced at the opposite upper and lower sides of the base B of my improvement, I provide the base with a pair of bosses or lugs 15 and 16, each having an opening extending therethrough and axially of the head as shown. Upon these bosses I mount a pair of forwardly extending, outwardly diverging, vertically flaring guiding prongs C, each having at its base a pair of dowels or cylindrically formed portions 17 and 18 projecting rearwardly from angular flanges or seats 19 and 20, formed at the base of each of the prongs C and integrally therewith as shown. The dowels 17 and 18 are preferably pressed into the opening in the lugs 15 and 16 and securely riveted therein at the rear face of such lugs as shown at 21 and 22, though they may,

100
105
110

if desired, be otherwise or removably mounted in the lugs as by means of a cotter pin or ordinary nut and thread. In cross section the wings or prongs C have the conformation illustrated at sections a, b and c of Figure 2 which gives to the prongs a guiding edge 23 which curves laterally of the head as illustrated, the curve of such edge at the base of the wings being but a slight curve 5 as illustrated at 24, but gradually increasing towards the forward end of the prongs until it embraces the entire guiding edge 23 of the prongs as shown, especially in Figure 2. At their base the guiding edge 23 of the 10 prongs lies in a horizontal plane and extends laterally of the base B at a right angle thereto, substantially on the transverse center line of the base B as shown. For a short distance in advance of the coupling face 11 of the base B the guiding edge 23 of the lower prong inclines downwardly from the transverse center line of the base B while such edge of the upper prong inclines upwardly from such center line, as at 24 of Figure 1. 15 Thus, when two of my improved coupling heads meet in the act of coupling the angularly disposed shoulder 24 of the prongs C rides upon the complementally formed surface 25 of the bosses 15. This engagement of the surfaces 24 and 25 serves to vertically align the base B of mating heads having my improvement and to maintain such heads in alignment. As shown, particularly in Figure 3, each of the prongs C extends forwardly from the coupling face 11 of the base B at an angle thereto for a short distance and thence flares outwardly, the angularity forming a vertically disposed bearing surface 26 adapted in coupling to mate with a complementally formed bearing surface 27 at the side of the base B. The mating of these 20 surfaces 26 and 27 assures accurate alignment of the base B of opposing coupling heads having my improvement, and hence, 25 in cooperation with surfaces 24 and 25 accurately align, and maintain in such alignment, the ports 7, 8 and 9 and the gaskets 10 of my improved support. It will be observed that the surfaces 27 flare laterally of 30 the base B and lie in the vertical plane and are integral with the surfaces 25 of the bosses 15, the base B being oblong in front view and provided with diagonally spaced upper and lower rounded corners 28 which join the surfaces 27 as shown. These rounded corners 28 cooperate with the curved portions a, b and c of the guiding edges 23 of the prong C to prevent jamming of the coupling heads in effecting coupling under conditions of extreme vertical and lateral disalignment. 35

Any suitable material may be used in the construction of my improved coupling head, but I preferably cast the base B thereof of any suitable metal, and drop-forged the prongs or guides C from steel or wrought

iron, providing them, for the purpose of greater strength, with ribs 29 which project forwardly of the prongs on the rear side thereof and are integral with the angular flanges or seats 19 and 20. This construction of head and guiding prong assures great strength and durability and produces a design which may be readily cast or drop-forged and economically machined and assembled. To assure proper positioning and 75 assembly of the prongs C on the base B the bosses 15 and 16 are drilled so as to have a definite relation to the ports 7, 8 and 9 and to the surfaces 25 and 27 of the base B, while the dowels 17 and 18 on the guiding 80 prongs C are machined to a definite relation with respect to the surfaces 24 and 26 thereof. Hence, when the prongs or wings C are assembled in the bosses 15 and 16 they are so related to the base B as to accurately align 85 the ports 7, 8 and 9 of mating heads and efficiently maintain them in such alignment under all conditions of service. Coupling heads constructed in this manner may be readily closely fitted, thus minimizing the 90 relative movement between mated heads and insuring a tight and efficient joint between the gaskets 10 thereof at all times. To reduce the weight of the base B, and to prevent the heat from the steam passing through the 95 port 9 of the base affecting the gasket or the air carried in the central or air brake port 8, I perforate the base B as at 30.

What I claim as new is:

1. An automatic train pipe coupling head, 100 comprising in combination, a base having a coupling face, a laterally extending integral projection on said base, said projection having a flat front face, a forwardly extending outwardly diverging guiding 105 prong constructed separate of said base and mounted on the front face of said projection, and means for securing said prong on said projection.

2. An automatic train pipe coupling head, 110 comprising in combination a base having a plurality of vertically aligned orifices extending therethrough and each carrying at its forward end a gasket, a plurality of vertically aligned nipples on the rear side of 115 said base and integral with the base and located concentrically with said orifices and projecting rearwardly of said base at a right angle to the coupling face thereof, lugs diagonally arranged on said base and integral with said base, each of said lugs having a flat front face upon which a guide prong may be secured. 120

3. An automatic train pipe coupling head, 125 comprising in combination a vertically disposed base having a plurality of vertically aligned openings therethrough and having also a flat coupling face lying in the vertical plane at a right angle to the longitudinal axis of the base, said base being oblong in 130

front view and being provided with upper and lower rounded corners and having also inclined bearing surfaces lying entirely in the vertical plane at the sides of said base 5 and adjacent to said rounded corners, a plurality of vertically aligned nipples formed integral with said base on the rear side thereof and extending rearwardly therefrom at a right angle to the coupling face 10 of the base, the nipples being substantially concentrically disposed with respect to said openings in said base, a gasket mounted in each of said openings, lugs formed integral with said base and diagonally disposed 15 thereon each of said lugs having a flat front face upon which a guiding prong may be secured.

4. An automatic train pipe coupling head, comprising in combination a vertically disposed base having a plurality of vertically aligned openings therethrough and having also a flat coupling face lying in the vertical plane at a right angle to the longitudinal axis of the base, said base being oblong in 25 front view and being provided with upper and lower rounded corners and having also inclined bearing surfaces lying entirely in the vertical plane at the sides of said base and adjacent to said rounded corners and 30 having also inclined bearing surfaces lying in the horizontal plane at opposite sides of said base and on substantially the transverse center line of the base, a plurality of vertically aligned nipples formed integral with 35 said base on the rear side thereof and extending rearwardly therefrom at a right angle to the coupling face of the base, the nipples being substantially concentrically disposed with respect to said openings in said base, 40 a gasket mounted in each of said openings, a pair of forwardly extending outwardly flaring vertically inclined guiding prongs separate of said base for aligning said gaskets with the gaskets of a counterpart coupling head, and means on opposite sides of 45 said base and positioned above and below the transverse center line of the base for securely attaching said guiding prongs to the base.

5. An automatic train coupling head, comprising in combination a base, a pair of projections formed integrally with the base, one of which projections is located above and the other of which is located below the transverse center line of the base and both 55 of which extend laterally of the base in opposite directions, each of said projections having a front bearing face extending transversely to the axis of the head, a pair of independent guiding prongs constructed separately of said base and mounted on said bearing faces of said projections and extending forwardly and laterally thereof, and means for securing each of said prongs in position on its respective one of said projections.

6. An automatic train pipe coupling head, comprising in combination, a vertically disposed base having a perforated projection at one side thereof, a forwardly extending outwardly vertically inclined guiding prong 70 having at its base a portion which projects into the perforation of said projection, and means for securely locking said portion in said perforation.

7. An automatic train pipe coupling head, 75 comprising in combination, a vertically disposed base having at one side thereof a projection which extends laterally of said base at substantially a right angle to the side thereof, said projection being located on substantially the transverse center line of said base and being provided with an inclined bearing surface, a guiding prong separate of said base and mounted on said projection and extending forwardly and laterally thereof, said prong being provided with a guiding edge which is inclined to correspond with the inclination of said projection and which is also located on substantially the transverse center line of said base and extends laterally of the base at substantially a 80 right angle to the side thereof whereby the inclined guiding edge of said prong mates with the complementary inclined bearing surface of said projection on an opposing head when counterpart heads couple up in service, and means for securing said guiding prong in position on said projection.

8. An automatic train pipe coupling head comprising in combination, a vertically disposed base having a transverse coupling face and being provided at diagonally opposite sides with bearing surfaces one of which lies in the vertical plane and another of which lies in the horizontal plane on substantially the transverse center line of said base, a seat on said base and located at one side thereof and above said transverse center line, another seat on said base and located at the side thereof opposite the side on which the first mentioned seat is located below said transverse center line, a pair of forwardly extending outwardly diverging guiding prongs one of which is mounted on each of said seats, said guiding prongs being provided at their bases with bearing surfaces lying one in the vertical plane and another in the horizontal plane and being adapted to mate with the aforesaid bearing surfaces of an opposing coupling head in coupling, and means for 100 properly securing said guiding prongs on said seats.

9. An automatic train pipe coupling head comprising in combination, a vertically disposed base provided at its opposite sides with a bearing surface which lies in substantially the horizontal plane and approximately on the transverse center line of said base, the base being provided also at such sides with a guiding edge which extends in the verti- 105 110 115 120 125 130

- cal plane for a substantial distance to form a seat for the guiding prong of a mating coupling head and thence flares inwardly towards the center of said base, a seat at opposite sides of said base and provided with an opening, a pair of diagonally spaced forwardly extending guiding prongs mounted one on each of said seats, and means extending into the opening in said seats for rigidly securing said prongs thereto.
10. An automatic train pipe coupling head, comprising in combination, a vertically disposed perforated base having at opposite sides inclined bearing surfaces one of which lies in the vertical plane and the other of which lies in the horizontal plane and on approximately the transverse center line of said base, a pair of perforated bosses extending laterally of said base and formed integrally therewith and positioned on diagonally opposite sides thereof, and a pair of independent prongs formed separately of said base and provided with cylindrical portions which extend axially of said base through the perforations in said bosses and are suitably secured therein, each of said prongs being provided with bearing surfaces adapted to mate with and conform to the aforesaid bearing surfaces at the sides of said base, the prongs being provided also with a guiding edge which changes from a substan-

tially flat surface lying at the base of the prongs to a curved surface as the guiding edge approaches the forward extremity of the prongs.

11. An automatic train pipe coupling head, comprising in combination, a vertically disposed base having a perforated projection, the front face of said projection lying in substantially the same plane as the front face of the base, a forwardly extending outwardly diverging guiding prong constructed separate of said base and mounted on said projection, the rear part of said prong having a member secured in a perforation of said projection.

12. An automatic train pipe coupling head, comprising in combination, a base having a flat coupling face arranged substantially at right angles to the longitudinal axis of the head, lugs integrally connected with said base and diagonally disposed on opposite sides thereof, each of said lugs having a front face lying in substantially the same plane as the coupling face of the base, a forwardly extending outwardly diverging guiding prong mounted on each of said lugs and means for securing said prongs to said lugs.

In testimony whereof I hereby affix my signature.

JOSEPH V. ROBINSON.
